Des. 220,014
Patented Feb. 23, 1971

220,014

DESK TRAY

Herbert M. Rome, Los Angeles, and Erland G. Paulson, Huntington Beach, Calif., assignors to Eldon Industries, Inc., Hawthorne, Calif., a corporation of California

Filed Jan. 19, 1970, Ser. No. 20,988

Term of patent 14 years

Int. Cl. D19—02
U.S. Cl. D74—9

FIG. 1.

FIG. 2.

FIG. 3.

FIG. 4.

FIG. 5.

FIG. 1 is a top plan view of a desk tray embodying the new design of our invention;

FIG. 2 is a front elevational view thereof;

FIG. 3 is a rear elevational view thereof;

FIG. 4 is a side elevational view as seen from the right of FIG. 2, the side opposite thereto being similar in appearance; and

FIG. 5 is a bottom plan view thereof.

I claim:

The ornamental design for a desk tray, substantially as shown and described.
